UNITED STATES PATENT OFFICE

2,579,767

PARALLEL MOTION ROLL CRUSHER

Orval R. Strawn, Columbus, Ohio, assignor to The Jeffrey Manufacturing Company, a corporation of Ohio

Application September 13, 1949, Serial No. 115,379

13 Claims. (Cl. 241—32)

1

This invention relates to a crusher, preferably of the double roll type.

An object of the invention is to produce such a crusher in which overload release mechanism is provided and one of the crusher rolls so mounted that when released it is guided and restrained so that its axis of rotation moves parallel toward and from another rotor by simplified and effective means including a rockable cross shaft.

Another object of the invention is to provide a crusher preferably of the above mentioned type in which idler means is brought into operation to take up the slack in the drive means of the releasable rotor whenever said rotor is released.

A further object of the invention is to provide a crusher, preferably of the above mentioned type, in which means including a hydraulic or other jack is provided to restore the removable roll to its normal position after the safety means has released it and preparatory to re-establishing the safety holding means.

Other objects of the invention will appear hereinafter, the novel features and combinations being set forth in the appended claims.

In the accompanying drawings,

Fig. 1 is a side elevational view of a double roll crusher incorporating the features of my invention;

Fig. 2 is a plan view of said crusher;

Fig. 3 is a sectional elevational view taken on the line 3—3 of Fig. 2, looking in the direction of the arrows;

Fig. 4 is an enlarged elevational view, with parts in section, taken on the line 4—4 of Fig. 2, looking in the direction of the arrows;

Fig. 5 is an enlarged view showing particularly the releasable support of the belt take-up of the releasable roll drive belt;

Fig. 6 is a sectional elevational view taken on the line 6—6 of Fig. 2, looking in the direction of the arrows;

Fig. 7 is a sectional elevational view showing the shear pin release mechanism and taken on the line 7—7 of Fig. 6, looking in the direction of the arrows;

Fig. 8 is a view similar to Fig. 7, taken at right angles thereto and on the line 8—8 of Fig. 6 of the drawings; and

Fig. 9 is a sectional view taken on the line 9—9 of Fig. 5 of the drawings.

As clearly illustrated, particularly in Figs. 1, 2 and 3 of the drawings, the double roll crusher which incorporates the features of my invention comprises a main frame 10 which includes a

2

bottom bed plate 11 having a central discharge opening 12 (see Fig. 3) through which reduced material is discharged from the housing or casing portion of said main frame which is formed of a plurality of welded plates including spaced side plates 13, 13, end plates 14 and 15 and removable top plates 16, 16, all of which cooperate to house a pair of rolls 17 and 18 provided with removable segmental liners having integral teeth thereon.

The main frame housing provides a central feed opening 19 through which material, such as coal, may be fed to the reducing chamber provided by said main frame housing 10, in which material is reduced between the oppositely rotating rolls 17 and 18 which rotate toward each other and size or reduce the material between them.

The roll 17 is provided with a shaft 20 which is mounted near opposite ends in a pair of journal bearings carried in bearing boxes 21, 21. Bearing boxes 21, 21 are slidably mounted between upper guide rods 22, one adjacent each side of the main frame and extending longitudinally thereof between end plates 14 and 15, and pairs of lower guide rods 23 which also extend between said end plates 14 and 15 and are supported upon box-like frame members, as clearly illustrated in Fig. 3 of the drawings.

The axis of rotation of the shaft 20 and roll 17 is adjustable in parallelism in a horizontal plane by threaded screw and nut adjusting mechanisms 24, there being one such mechanism associated with each of the bearing boxes 21. Each adjusting mechanism is effective by rotating the threaded shaft thereof by ratchet devices 25 which are preferably interconnected by cross rod 26, thus insuring the uniform adjustment of the two bearing boxes 21 so as to adjust the roll 17 toward and from the roll 18.

One end of the shaft 20 is provided with a drive pulley 27 driven from an electric motor 28 through appropriate multiple V-belt drive mechanism 29. As suggested in Figs. 1 and 2 of the drawings, the motor 28 may be adjusted in position to maintain proper tension on the multiple belt drive mechanism 29.

The roll 18 is provided with a shaft 30 (see particularly Fig. 3) which is supported near opposite ends in appropriate journal bearings carried in bearing boxes 31, 32 and at one free end is provided with the drive pulley 33 of a multiple V-belt drive mechanism 34 driven from an electric motor 35. The two bearing boxes 31 and 32 are mounted for sliding movement between the upper and lower guide rods 22 and 23, as

clearly illustrated in Fig. 3 of the drawings, which provides for movement of the axis of rotation of the roll 18, which is the axis of the shaft 30, in parallelism towards and from the axis of rotation of the roll 17, in a horizontal plane.

The roll 18 is releasably held with its axis of rotation in a predetermined position by mechanism including overload shear pin release means so that in response to an overload said roll 18 may move in a horizontal plane and in parallelism to the right, as viewed in Figs. 1 and 2 of the drawings. To this end each of the bearing boxes 31 and 32 is provided with a rearwardly extending operating link, that for box 32 being designated 36. As the structure of the two links and associated mechanism is similar, it will only be necessary to describe link 36 and its associated mechanism.

Said link 36 is pivoted at its forward end to the bearing box 32 and at its rear end it is pivotally attached to a bifurcated pivot arm 37 rigidly attached, as by welding, to one end of a cross or rock shaft 38, the opposite end of which carries a bifurcated pivot arm 39 (see Fig. 2) similar to pivot arm 37. That is, the radial pivot arms 37 and 39 are rigidly attached to the cross shaft 38 and at their upper ends are pivoted to horizontally positioned links, one of which is seen at 36, which connect said arms 37 and 39 to the bearing boxes 32 and 31, respectively.

The cross shaft 38 is mounted for limited rotary or swinging movement on a transverse horizontal axis relative to the main frame 10 by means of three spaced bearings 40. It is thus evident that the rotor or roll 18 is mounted so that its axis of rotation is adjustable in a horizontal plane in parallelism, since the two ends of the shaft 30 thereof are interlinked to require equal movement thereof as the roll or rotor slides backwardly or forwardly relative to the main frame 10. Substantially transversely centrally of the rock shaft 38 there is a bifurcated pivot arm 41 welded thereto which is essentially of the same construction as bifurcated arms 37 and 39.

As clearly illustrated in Figs. 6, 7 and 8 of the drawings, the end plate 15 carries a rearwardly extending boss 42 which has a rectangular notch therein receiving a removable block 43 removably held in position by means including a set screw 44. The block 43 is adapted to receive a pair of hardened steel bushings 45 removably held in position by set screws 46 (see Fig. 7). Similar hardened bushings 47 are mounted in the two branches of the pivot arm 41 and are removably held by set screws 48.

In the normal position of the parts, as illustrated, for example, in Figs. 1, 2 and 4 of the drawings, the bushings 45 and 47 will be in alignment and a shear pin 49 will extend through and have close fit with aligned central bores in said bushings. Whenever an overload occurs the shear pin 49 will be sheared in two places adjacent the abutting ends of bushings 45 and 47 and permit the cross shaft 38 to pivot, swing or rotate a limited amount, allowing the rotor or roll 18 to move away from the roll 17 while the axis thereof moves in a horizontal plane in parallelism so that there is a uniform opening between the two rolls and so as to prevent any binding between the shaft 30 and its associated bearings or in other parts of the unit.

It is obvious that when such overload movement of the roll or rotor 18 occurs, slack will be developed in the multiple V-driving belt of the drive mechanism 34. To maintain said belt

in proper relation with the associated pulleys an automatic slack take-up mechanism is provided which is indicated generally by the reference character 50. Said slack take-up mechanism includes an idler pulley 51 which preferably, though not necessarily, is normally held just above and out of contact with the associated belt of the drive mechanism 34. It is carried on a pivoted arm 52 which is biased for downward movement by a spring 53. The pivoted arm 52 is rigidly attached to a stub shaft 54 mounted for limited rotation on a bracket 55 carried by the end plate 15.

Stub shaft 54 extends to the right of the bracket 55, as viewed in Fig. 5 of the drawings, and is provided with a radially extending integral key 56 which when the parts are in their normal positions rests on the top of a supporting headless screw 57 which is adjustably mounted on the free outer end of the link 36. The key 56, under normal conditions resting on the head 57, will hold the arm 52 in position to maintain the idler pulley 51 out of contact with the associated V-belts of the drive mechanism 34.

Whenever the overload shear pin 49 is sheared, allowing the bearing box 32 to move rearwardly, it is obvious that the screw 57 will move from under the key 56, releasing the arm 52 so that the idler pulley 51 will fall by gravity and under the influence of the spring 53 to take up the slack in the driving belt for the pulley 33 and roll or rotor 18, thus preventing damage thereto.

Whenever the shear mechanism is operated, together with the automatic slack take-up mechanism 50, it is, of course, necessary to provide a new shear pin 49 and to restore the parts to their normal positions of operation. To aid in this operation insofar as the automatic take-up mechanism 50 is concerned, said mechanism includes a holding pawl 58 (see Fig. 9) which cooperates with the ledge of a boss 59 carried by the arm 52 to hold the arm 52 in its upper position temporarily while the link 36 extends rearwardly such an amount that screw 57 is rearward of the key 56. The pawl 58 is pivoted to one arm of the bracket 55. It has a downwardly extending leg, as clearly illustrated in Fig. 9 of the drawings, adapted to be contacted by an extension of a pivot pin 60 which pivotally connects the above mentioned link 36 with the pivot arm 37 so that when the link 36 is moved to its normal position and the headless screw 57 is beneath the key 56, the pawl 58 is released from the boss 59 so that control of the pivot arm 52 will again be restored to the link 36 under the control of roll 18.

Also to aid in restoring the parts to their normal positions for re-insertion of a new shear pin 49 is a jack preferably carried by the main frame 10. In the form illustrated there is a jack 61 (see Figs. 2 and 6) which under normal conditions is carried by appropriate bracket means on the plate 15, said jack, as illustrated, including a pump portion 62 which may be operated by a handle, and a ram portion 63, the two parts being connected by a flexible hose since the complete jack includes fundamentally a hand pump and connected ram or cylinder of a hydraulic jack unit.

To restore the parts to their normal positions, or, in other words, to rock the shaft 38 and move the roll 18 and pulley 33 back into position, the cylinder part of the ram 63 of the jack has a trunnion head adapted to be received by a bracket 64 connected to the plate 15 of the

main frame 10. The piston rod of said ram 63 has a cross shaft adapted to be received in U-bracket means 65 (Fig. 6) carried by one of the branches of the bifurcated pivot arm 41.

It is thus evident that upon expansion of the ram 63, the rock shaft 38 may be rotated in a counter-clockwise direction, as viewed in Figs. 1, 4 and 6 of the drawings, thereby restoring the roll 18 to its normal position so that a new shear pin 49 may be inserted between the bushings 45, 47. It is, of course, evident that during this restoring operation the pivot arm 52 is held in elevated position by the pawl 58, which pawl is disengaged to restore the automatic character of the automatic slack take-up mechanism as soon as the roll 18 reaches its normal position.

In the operation of the device the two rolls or rotors 17 and 18 will rotate in reverse directions, roll 17 rotating clockwise and roll 18 rotating counter-clockwise, as viewed in Fig. 1 of the drawings. Should an overload occur, such as might be caused by a large piece of tramp metal or any unusually hard material, particularly of large size, such as might normally do damage to the machine, the shear pin 49 will be double sheared and allow the roll or rotor 18 to move in a horizontal plane and in parallelism away from the roll 17, the axis of the rotor 18 moving in parallelism at all times. This movement will be accompanied by rocking or limited rotation of the shaft 38 and the automatic release through the headless bolt 57 and key 56 of the slack take-up mechanism 50 which will operate to take up the slack in the belt of the drive for the roll or rotor 18, with the idler 51 riding on the upper run of the belt of said drive. When such release has taken place the operator will shut down the crusher by stopping the motors 28 and 35 and re-establishing the normal conditions as above set forth, whereupon the unit will be ready to be placed in operation again.

Obviously those skilled in the art may make various changes in the details and arrangement of parts without departing from the spirit and scope of the invention as defined by the claims hereto appended, and applicant therefore wishes not to be restricted to the precise construction herein disclosed.

Having thus described and shown an embodiment of the invention, what it is desired to secure by Letters Patent of the United States is:

1. A double roll crusher including a frame, a roll mounted on said frame for rotation on an axis, a second roll mounted on said frame for rotation parallel with the axis of said first roll, means mounting said second roll for parallel motion toward and from said first roll, said mounting means including slidable bearings supporting opposite ends of said second roll, a rockable cross shaft, linkages including radial arms on said rockable cross shaft interconnecting said bearings to opposite ends of said cross shaft, and shear pin means for releasably holding said rock shaft against rocking movement whereby said second roll is held in its operating crushing position.

2. A double roll crusher including a frame, a roll mounted on said frame for rotation on an axis, a second roll mounted on said frame for rotation on an axis parallel with the axis of said first roll, means mounting said second roll for parallel motion toward and from said first roll, said mounting means including slidable bearings supporting opposite ends of said second roll, a rockable cross shaft, linkages including radial

arms on said rockable cross shaft interconnecting said bearings to opposite ends of said cross shaft, and means for releasably holding said rock shaft against rocking movement whereby said second roll is held in its operating crushing position.

3. A double roll crusher including a frame, a roll mounted on said frame for rotation, a second roll mounted on said frame for rotation parallel with said first roll, means mounting said second roll for parallel motion toward and from said first roll, said mounting means including slidable bearings supporting opposite ends of said second roll, means yielding normally holding the axis of rotation of said second roll in a predetermined position, driving means for said second roll including a flexible drive belt, and normally inoperative idler means operable responsive to lateral movement of said second roll from said axis of rotation in response to overload to take up the slack in said drive belt.

4. A crusher including a rotor, means cooperating with said rotor to crush material, means yielding normally holding said rotor for rotation on a fixed axis, driving means for said rotor including a flexible drive belt, and normally inoperative idler means operable responsive to lateral movement of said rotor axis of rotation to take up the slack in said drive belt.

5. A double roll crusher including a frame, a roll mounted on said frame for rotation on an axis, a second roll mounted on said frame for rotation on an axis parallel with the axis of said first roll, means mounting said second roll for parallel motion toward and from said first roll, said mounting means including slidable bearings supporting opposite ends of said second roll, a rockable cross shaft, linkages including radial arms on said rockable cross shaft interconnecting said bearings to opposite ends of said cross shaft, means for releasably holding said rock shaft against rocking movement whereby said second roll is held in its operating crushing position, and jack means carried by said frame for moving said second roll to its normal operating position.

6. A crusher including a frame, a rotor mounted on said frame for normal rotation on a predetermined axis, means cooperating with said rotor to crush material, bearing means for opposite ends of said rotor, means yielding locking said bearing means against movement, said means including a rocking cross shaft, linkages including radially movable arms connecting said bearing means to said rocking cross shaft, and means releasably locking said shaft against rocking movement said releasable locking means being releasable when said rotor exerts excessive crushing pressure to release said bearings and rotor whereby the latter may move with respect to said cooperating crushing means.

7. A crusher including a frame, a rotor mounted on said frame for normal rotation on a predetermined axis, means cooperating with said rotor to crush material, bearing means for opposite ends of said rotor, means yielding locking said bearing means against movement, said means including a rocking cross shaft, linkages including radially extending arms on said rocking cross shaft connecting said bearing means to said rocking cross shaft, means releasably locking said shaft against rocking movement, means for driving said rotor including a belt, and take up means operable automatically upon lateral movement of the normal axis of rotation of said

rotor to take up the slack in said belt, said take-up means having a releasable latch normally holding it out of contact with said belt.

8. A crusher including a frame, a rotor mounted on said frame for normal rotation on a predetermined axis, means cooperating with said rotor to crush material, bearing means for opposite ends of said rotor, means yieldingly locking said bearing means against movement, said means including a rocking cross shaft, linkages including radially extending arms on said rocking cross shaft connecting said bearing means to said rocking cross shaft, means releasably locking said shaft against rocking movement, means for driving said rotor including a belt, and normally inoperative take-up means operable automatically upon lateral movement of the normal axis of rotation of said rotor to take up the slack in said belt.

9. A crusher including a frame, a rotor, shaft means for said rotor mounted on said frame for normal rotation on a predetermined axis, a pulley on said shaft, bearing means for opposite ends of said shaft means, means yieldingly holding said bearing means and shaft against lateral movement, a drive pulley, endless belt means interconnecting said pulleys, a normally inoperative belt take-up means, and means responsive to lateral movement of said shaft means from its normal axis of rotation for causing said normally inoperative belt take-up means to engage said endless belt means whereby the latter cannot be thrown from said pulleys by reason of slack therein.

10. A crusher including a frame, a rotor, a pulley for driving said rotor, bearing means supporting said rotor and pulley on said frame for normal rotation on a predetermined axis, means yieldingly holding said rotor and said pulley against lateral movement, a drive pulley, endless belt means interconnecting said pulleys, a normally inoperative belt take-up means, and means responsive to lateral movement of said rotor and pulley from their normal axis of rotation for causing said normally inoperative belt take-up means to engage said endless belt means whereby the latter cannot be thrown from said pulleys by reason of slack therein.

11. A crusher including a frame, a rotor, a pulley for driving said rotor, shaft means for

5 said pulley, bearing means supporting said shaft and pulley on said frame for normal rotation on a predetermined axis, means yieldingly holding said pulley against lateral movement, a drive pulley, endless belt means interconnecting said pulleys, a normally inoperative belt take-up means, and means responsive to lateral movement of said pulley from its normal axis of rotation for causing said normally inoperative belt

10 take-up means to engage said endless belt means whereby the latter cannot be thrown from said pulleys by reason of slack therein.

12. A crusher including a frame, a rotor, a pulley for driving said rotor, shaft means for said pulley, bearing means supporting said shaft and pulley on said frame for normal rotation on a predetermined axis, a drive pulley, endless belt means interconnecting said pulleys, a normally inoperative belt take-up means, and means

15 responsive to lateral movement of said pulley from its normal axis of rotation for causing said normally inoperative belt take-up means to engage said endless belt means whereby the latter cannot be thrown from said pulleys by reason of slack therein.

13. In combination, a frame, a shaft, a pulley on said shaft, bearing means supporting said shaft and pulley on said frame for normal rotation on a predetermined axis, a drive pulley, endless belt means interconnecting said pulleys, a normally inoperative belt take-up means, and means responsive to lateral movement of said pulley from its normal axis of rotation for causing said normally inoperative belt take-up means to engage said endless belt means whereby the latter cannot be thrown from said pulleys by reason of slack therein.
